United States Patent

Des. 236,355
Patented Aug. 19, 1975

236,355

MICROPHONE OR SIMILAR ARTICLE

Peter Quay Yang, New York, N.Y., assignor to
Lanier Electronic Laboratory, Inc., Atlanta, Ga.

Filed Apr. 1, 1974, Ser. No. 456,595

Term of patent 14 years

Int. Cl. D14—01

U.S. Cl. D26—14 J

FIG. 1

FIG. 2

FIG. 3

FIG. 4

FIG. 5

FIG. 1 is a perspective view of a microphone embodying the design of the present invention;

FIG. 2 is a right side view of the microphone;

FIG. 3 is a top plan view thereof;

FIG. 4 is an inverted left side view thereof; and

FIG. 5 is a bottom plan view thereof.

I claim:

The ornamental design for a microphone or similar article, substantially as shown.
